UNITED STATES PATENT OFFICE

CHARLES LEO FITZ, OF CHICAGO, ILLINOIS, ASSIGNOR TO Q. R. S.-DE VRY CORPORATION, OF CHICAGO, ILLINOIS, A CORPORATION OF ILLINOIS

DESIGN FOR A COMBINED SIDE MEMBER AND EXPOSURE METER FOR CAMERAS

Application filed October 6, 1930. Serial No. 37,145. Term of patent 7 years.

To all whom it may concern:

Be it known that I, CHARLES LEO FITZ, a citizen of the United States, residing at Chicago, in the county of Cook and State of Illinois, have invented a new, original, and ornamental Design for a Combined Side Member and Exposure Meter for Cameras, of which the following is a specification, reference being had to the accompanying drawing, forming part thereof.

The figure is an elevational view of a com-

bined side member and exposure meter for cameras, showing my new design. The article is substantially flat and of no appreciable thickness. It is used as a cover for one side of a camera.

I claim:

The ornamental design for a combined side member and exposure meter for cameras as shown and described.

CHARLES LEO FITZ.
